UNITED STATES PATENT OFFICE.

RICHARD A. F. BEILFUSS, OF LANSING, MICHIGAN.

GAS OR VAPOR ENGINE.

SPECIFICATION forming part of Letters Patent No. 730,084, dated June 2, 1903.

Application filed July 15, 1901. Serial No. 68,391. (No model.)

To all whom it may concern:

Be it known that I, RICHARD A. F. BEILFUSS, a citizen of the United States, residing at and whose post-office address is Lansing, in the county of Ingham and State of Michigan, have invented new and useful Improvements in Gas or Vapor Engines, of which the following is a specification.

My invention relates to gas and vapor engines; and the object thereof is to produce an exhaust-valve and igniter of new and improved character and new and improved means for operating the exhaust-valve and igniter.

15 A further object of the invention is to provide means of a novel character to control the speed of the engine.

Still further objects of the invention will appear as the nature of the same is more fully understood from the following description, taken in connection with the accompanying drawings.

With the above general objects in view the invention consists in the novel construction, combination, and arrangement hereinafter fully described, illustrated, and claimed.

In the accompanying drawings, Figure 1 is a vertical sectional view through a gas-engine constructed in accordance with the present invention, said section being taken in line with the crank-shaft. Fig. 2 is a section taken at right angles to Fig. 1 and in line with the igniter and exhaust-valve stem, the section also passing through the suction-pipe, needle-valve, &c. Fig. 3 is a detail longitudinal section through the muffler. Fig. 4 is a detail elevation of the collar or cam which oscillates the igniter and exhaust-valve stem. Fig. 5 is a detail sectional view of the ignition-chamber on the line xx looking down and illustrating the relative positions of the members of the igniter.

Like numerals of reference denote like parts in all the figures.

45 Referring to the drawings, 1 designates a suitable base upon which the remainder of the engine is mounted for its support, said casing having bolted thereto and supported thereon the cylinder-frame 2, the upper portion of which comprises the main cylinder 3 of the engine. Within said cylinder is mount-

ed a reciprocatory piston-head 4, which is connected, by means of a pitman or connecting-rod 5, with the crank-shaft 6, the latter being journaled in bearing-boxes 7, supported on the base 1, and the shaft being further provided with balance or fly wheels 8, which are fastened to the shaft by means of keys 9 or in any other convenient manner. The connecting-rod 5 is provided at its opposite ends with means for taking up wear where it connects with the crank-shaft and also where it connects with a transverse pin or shaft 10, extending across the interior of the piston-head 4, said shaft being held in place by means of set-screws 11, while wear-plates 12 or cut bushing are interposed between the end of the connecting-rod 5 and said shaft and supported by means of an adjusting-screw 13. The shaft 10 is further provided with an oil-passage 14, by means of which the necessary supply of oil is fed to the pin or shaft 14. The piston-head is further provided with annular grooves in its outer surface, in which are placed packing-rings 15.

The main body of the cylinder 3 is recessed in its outer surface to form a water-space 16, which is inclosed by means of a jacket 17, the lower edge of which is removably fitted in an annular groove 18 in the bottom of the cylinder, while its upper edge is received in a flange 19, adjacent to the upper head of the cylinder, the upper head being also jacketed or provided with a water-space 20.

21 designates a suction-pipe arranged at one side of the crank-shaft and extending vertically, said pipe being provided at its upper end with an elbow and connection 22, leading to the suction-valve casing 23, the lower portion of which is formed with a seat 24 against which operates the suction-valve 25, having its stem 26 extending upward through the valve-chamber and provided with a cap 27 on its upper and exteriorly-arranged end, said cap receiving the outward pressure of one end of a coiled spring 28, which surrounds the valve-stem, with its inner end bearing against the valve-casing, as clearly illustrated in Figs. 1 and 2, the spring serving by its tension to hold the valve normally closed, but yielding to permit the flow of gas or vapor past the valve into the explosion-

chamber 28 in the upper end of the cylinder under the influence of the suction caused by the downward movement of the piston-head 4.

29 designates the exhaust-valve chamber, the upper end of which is provided with a seat for the exhaust-valve 30, said valve being mounted loosely upon its stem 31, which is movable longitudinally for seating and unseating the valve 30. The discharge end of the exhaust-valve casing 29 is interiorly screw-threaded to receive the threaded extension 32 of the inner perforated tube 33 of the muffler 34, which is in the form of a hollow cylinder, one end of which is provided with a head 35, screwing upon the inner tube 33, and the opposite end of which is provided with a similar head 36, interiorly threaded to receive a pipe leading outward therefrom to any suitable point of final exhaust. The inner extremity of the tube 33 is closed by a cap 37, so that the exhaust is sprayed outward through a multiplicity of openings in the tube 33, thus spreading and scattering the force of the explosions and deadening the sound before escaping from the outer cylinder.

Between the chambers 23 and 29 there is arranged an ignition-chamber 37, such chamber being located between the suction and exhaust valves. Projecting into said chamber is the inner terminal of a binding-post 38, constituting the stationary member of an igniter, and with which connects a suitable electrical conductor 39 from a dynamo or spark-coil. Upon the upper end of the stem 31 is mounted the movable member of the igniter, and it is in the form of a metal arm 40, extending laterally from the extremity of the stem, whereby under an oscillatory movement of the stem 31 the electrical contact is made and broken, thereby emitting a spark, which explodes a charge of gas or vapor contained in the ignition-chamber 37, explosion or combustion chamber 28, and air and gas passage 41, leading from the ignition-chamber to the explosion-chamber. The exhaust-valve 30 is held normally closed by means of a coiled spring 42, which is interposed between the lower end of the exhaust-chamber and a collar or spring-seat 43, surrounding the stem 31 and adjustable up and down thereon by means of a binding-screw 44, thus adapting the force with which the valve is seated to be regulated.

I will now proceed to describe the mechanism for imparting an oscillatory as well as reciprocatory movement to the valve-stem 31. Adjacent to its lower end the valve-stem 60 passes through a guide 45 in the form of a sleeve carried by the arm of a bracket 46, which is secured for convenience to the cylinder 3 or cylinder-frame. The guide 45 is provided with a notch or slot 47, in which works a pin 48, projecting laterally from the stem 31, the slot 47 being of such width or size as to

admit of the necessary oscillatory movement of the stem, while limiting the degree of oscillation thereof. In order to oscillate the stem 31, the latter is provided at its lower end 70 with a yielding spring-arm 49, which projects laterally therefrom, so as to be operated upon by a cam-shaped projection 50 on a collar 51, which is rotated by gearing hereinafter described. Under the rotary movement of the collar 51 the projection 50 strikes against the arm 49, and thereby operates to partially turn the stem 31 in one direction. After the projection 50 passes out of contact with the arm 49 the stem 31 is returned to its normal position by means of a coiled spring 42, which acts spirally or with a torsional action as well as an expansion-spring, the spring thus serving not only to reseat the exhaust-valve, but also to normally maintain the contact between 85 the igniter 40 and binding-post 38.

The crank-shaft 6 is provided at a suitable point with a spur-pinion 52 of half the number of teeth, which meshes into a spur gear-wheel 53, having twice the number of teeth 90 as the pinion 52. The wheel 53 is mounted upon a stud-shaft 54, carried by the bracket 46, and said wheel 53 is mounted upon a hub-sleeve 55, which rotates upon the stud-shaft 54 and also carries with it the rotary collar or 95 cam 50, which operates upon the arm 49, as hereinabove described, the arrangement of the gear-wheel serving to impart one complete movement to the arm 49 to every two revolutions of the crank-shaft, the engine 100 thus being of what is known as the "four-cycle" type. The wheel 53 has projecting from one side thereof a stud 56, upon which is journaled an antifriction-roller 57, which operates against a foot 58, arranged at the 105 lower end of the stem 31, said foot being carried by a sleeve 59, surrounding the stem 31 and screwing thereon and being locked by means of a jam-nut 60. Thus in every two revolutions of the crank-shaft and in each 110 revolution of the gear-wheel 53 the roller 57 operates against the foot 58 to impart a longitudinal movement to the valve-stem 31, thereby unseating the exhaust-valve and allowing the exhaust to pass into the muffler. 115

In connection with the engine hereinabove described I employ a speed-regulating device which comprises a pair of segmental arms 61, which are pivotally connected with a projection on the hub of one of the balance-wheels 120 and have a shouldered engagement at one side, as at 62, so as to cause both of the arms to move equally, while said arms are connected at their opposite free ends by means of a yoke-spring 63. One of the arms 61 is connected 125 by a pivotal link 64 with a weighted arm 65, pivotally connected at 66 with the balance-wheel and having the free end thereof connected, by means of a resistance-spring 67, with another portion of the wheel by means 130 of an adjustable screw 68, by means of which the tension of the spring 67 may be regulated.

Under the rapid rotation of the crank-shaft the arms 61 are caused to move outward under the influence of the weighted arm, and thereby to press outward the curved portion 5 69 of a rocker-arm 70, provided with a bearing 71, by which it is journaled on the stud-shaft 54, said rocker-arm being provided at its opposite or upper end with a catch 72, adapted under the rapid rotation of the crank-shaft and balance-wheels to be moved beneath a governing-catch 73 on the stem 31 for the purpose of defeating the closing of the exhaust-valve, and thus reducing the force of the explosions and their effect against the 10 piston-head. When the speed of the crank-shaft has been materially reduced, the catches are moved out of engagement with each other, so as to allow the exhaust-valve to resume its normal position. 74 designates an air-release 15 cock, which communicates with the interior of the cylinder 3, and 75 represents a lubricating-pipe leading to the interior of the cylinder.

Within the suction-pipe 21 is mounted a 20 brass tube 76, which is enough smaller than the suction-pipe to leave a surrounding annular space, the upper end of the tube 76 being open and the lower end thereof closed and provided with an elbow 77, which communicates with a needle-valve casing 78, projecting laterally from the suction-pipe. Within the casing 78 is mounted a needle-valve 79, having at its outer extremity an operating head or button 80.

81 denotes an oil-supply pipe, which communicates with the needle-valve chamber for supplying oil thereto. The oil passes into the tube 76 through the needle-valve opening, where it is vaporized and mixed with the 35 air passing upward through the suction-pipe 21 into the suction-chamber, from which it is subsequently drawn into the combustion-chamber and exploded by the means hereinabove described.

40 From the foregoing description it will be seen that the valve-stem 31 performs the double duty of opening the exhaust-valve and operating the igniter, which is accomplished by imparting both a reciprocatory and an oscillatory movement to the stem, this arrangement being quite advantageous as compared with prior constructions, in which separate stems or parts were necessary to perform the two operations referred to. It will also be 45 seen that the coiled spring 42 operates both to seat the exhaust-valve and retract the igniter after it has been operated upon by the stem-oscillating mechanism hereinabove described. It will also be seen that the anti-friction-roller 57 operates both to unseat the exhaust-valve and release the governing catches.

50 The engine above described is simple, economical, and direct in action. There is little liability of the working parts of the engine getting out of order, and on account of the accessibility of the parts the engine may be

kept in running order with little trouble and at a minimum expense. The waste of gasoline or vapor is also to a great extent dispensed with, and the further supply of oil may be regulated by the needle-valve. In case of fracture the water-jacket may be removed and replaced at small expense and without great trouble, as it is easily disassociated from the cylinder.

55 It will be apparent that the invention is susceptible of various changes in the form, proportion, and minor details of construction, which may accordingly be resorted to without departing from the principle or sacrificing any of the advantages of the invention.

Having thus described the invention, what is claimed as new, and desired to be secured by Letters Patent, is—

60 1. In a gas or vapor engine, the combination with a valve-stem, of an exhaust-valve mounted thereon, an electric circuit, a stationary member of an igniter interposed in the circuit, a movable member of the igniter interposed in the circuit and rigidly mounted on the stem, a single spring for normally retaining the exhaust-valve closed, and the igniter in position to close the circuit, and means for imparting motion to the stem, to 65 unseat the valve and to operate the igniter.

65 2. In a gas or vapor engine, the combination with a valve-stem, of an exhaust-valve mounted thereon, an electric circuit, a stationary member of an igniter interposed in the circuit, a movable member of the igniter interposed in the circuit and rigidly mounted on the stem, a single spring for normally retaining the exhaust-valve closed and the igniter in position to close the circuit, means 70 for imparting to the stem reciprocatory and oscillatory motions, and means for limiting the oscillatory motion of the stem.

75 3. In a gas or vapor engine, the combination with a valve-stem, of an exhaust-valve mounted thereon, an electric circuit, a stationary member of an igniter interposed in the circuit, a movable member of the igniter interposed in the circuit and rigidly mounted on the stem, a single spring for normally retaining the exhaust-valve closed, and the igniter in position to close the circuit, means 80 for imparting to the stem reciprocatory and oscillatory motions, a sleeve provided with a notch, and a pin carried by the stem, and adapted to be received by the notch whereby the oscillatory motion of the stem is limited.

85 4. In a gas or vapor engine, the combination with a valve-stem, of an exhaust-valve mounted thereon, an electric circuit, a stationary member of an igniter interposed in the circuit, a movable member of the igniter interposed in the circuit and rigidly mounted on the stem, a single spring for normally retaining the exhaust-valve closed and the igniter in position to close the circuit, means 90 for imparting to the stem reciprocatory and oscillatory motions, a sleeve provided with a notch, a pin carried by the stem, and adapted 95 to 100

to be received by the notch whereby the oscillatory motion of the stem is limited, a governing-catch mounted upon the stem, a rocker-arm, and a pair of segmental arms adapted to
5 separate under excessive speed to throw the rocker-arm in engagement with the governing-catch to unseat the exhaust-valve.

In testimony whereof I affix my signature in presence of two witnesses.

RICHARD A. F. BEILFUSS.
